FRONT PANEL FOR A ROOM AIR CONDITIONER

Philip S. Egan, Glenview, Ill., assignor to Sears, Roebuck and Co., Chicago, Ill., a corporation of New York

Application September 6, 1957, Serial No. 47,627

Term of patent 3½ years

(Cl. D62—4)

The drawing is a plan view of a front panel for a room air conditioner embodying my new design.

The panel is of no substantial thickness and the sides are plain.

I claim:

The ornamental design for a front panel for a room air conditioner, as shown and described.
